ABSTRACT

A cooling pillow has a cooler module, a heatsink module. The heatsink module is formed in the cooler module. The peltier cooler has a bottom side and a top side. The peltier cooler transfers heat from the bottom side of the peltier cooler to the heatsink module. The water tube absorbs heat from the heatsink module. The fiberglass bottom stabilizes the heatsink module. The fiberglass bottom also insulates the heat within the cooler module. The pressure sensor is formed in the cooler module. The pressure sensor measures pressure from the user. The pillow antenna is formed within the cooler module.

1
COOLING PILLOW

FIELD OF THE INVENTION

The present invention is in the field of cooling pillows.

REFERENCE TO RELATED ART

A variety of different cooling pillows have been described in patent publications. For example, an invention that involves the use of a pillow to cool a user's head is CN Pat. No. 205030925 to Xihua University, entitled Built-In Semiconductor Refrigeration Piece Water-Cooling Pillow, having an issue date of Feb. 17, 2016, the disclosure of which is incorporated herein by reference. It is a cooling pillow made in China that has a fan that cools aquogel which cools itself through the radiator on the bottom. It also has two fans on the back side that cool the radiator. It could be loud and aquogel is difficult to find.

A water cooled pillow is described TW patent No. 201225890 to Fu-Jing Cheng, entitled Water-Cooled Pillow Structure, having an issue date of Jul. 1, 2012, the disclosure of which is incorporated herein by reference. The pillow is made of a hard material that dissipates heat. It is made in Taiwan and has a water bag inside that is curved in a wavy shape to provide comfort.

An invention that involves the use of Peltier cooling modules to cool a pillow is US patent No. 20190307270 to Ronald D. Blum and Amitava Gupta, entitled Cooling Pillow, having an issue date of Oct. 10, 2019, the disclosure of which is incorporated herein by reference. With an abandoned patent, this cooling pillow has cubic modules of phase change material close to the surface where the head is placed and uses a Peltier module to cool the strips of phase change material. This looks very uncomfortable and has many figures with cooling strips placed in different areas.

An invention that involves the use of compressed air to cool a pillow is US patent No. 2018014011 to Marc L. Werner, entitled Cooling Pillow, having a publication date of May 24, 2018, the disclosure of which is incorporated herein by reference. This pillow has phase change material and has many holes around the foam that takes in air like a sponge. When compressed, the air inside the pillow cools down the phase change material within the pillow which cools the pillow. This seems impractical as once the pillow loses all of its air, one would have to let it re-inflate itself.

An invention that involves the use of thermoelectric cooling to cool a pillow is U.S. Pat. No. 3,648,469 to James E Chapman, entitled Cooling Pillow, having a publication date of Mar. 14, 1972, the disclosure of which is incorporated herein by reference. This pillow has a radiator in the middle that picks up heat from one side of the pillow and transfers it to the other side. It uses electric current with the Peltier effect in order to transfer the heat. This type of cooling would be quite situational as people who sleep with their arm(s) under their pillow would have warm arms.

SUMMARY OF THE INVENTION

A cooling pillow has a cooler module, a heatsink module. The heatsink module is formed in the cooler module. The peltier cooler has a bottom side and a top side. The peltier cooler transfers heat from the bottom side of the peltier cooler to the heatsink module. The water tube absorbs heat from the heatsink module. The fiberglass bottom stabilizes the heatsink module. The fiberglass bottom also insulates the heat within the cooler module. The pressure sensor is formed

2

in the cooler module. The pressure sensor measures pressure from the user. The pillow antenna is formed within the cooler module.

The connected device is connected to the pillow antenna. 5 The light strip is connected to the pressure sensor. The light strip lights up according to the connected device. The fan is formed in the cooler module. The fan blows air onto the heatsink module. The pillow case is situated around the pillow. The pillow cover is situated around the pillow case. 10 The pillow cover passively cools the user. The air conduit releases air from the fan. The fan transfers heat from the heatsink out of the air conduit. The foam body surrounds the cooler module columns. The foam body is infused with phase change material gel. The electrical plug powers the 15 cooler module columns. The cooler module column comprises of 10 cooler modules, all parallel to one another. The cooler module column is powered by the electrical plug. The cooler module cools the phase change material pack. The phase change material pack casing encloses the phase change material pack. The wireless connector includes a connection to the connected device. The wireless connector is configured to receive control signals from the connected device. The radiator is a passive cooling radiator. The water tube transfers heat.

BRIEF DESCRIPTION OF THE DRAWINGS

FIG. 1 is a top cross section view of the present invention.

FIG. 2 is a side cross section view of the present invention.

FIG. 3 is an exploded view.

FIG. 4 is a detail view of the Cooler Module.

The following callout list of elements can be a useful guide in referencing the element numbers of the drawings.

430 Upper ceramic substrate
440 Lower ceramic substrate
450 Pressure sensor

460 Pressure sensor backing
470 Thermoelectric Legs

5 DETAILED DESCRIPTION OF THE
PREFERRED EMBODIMENT

As seen in FIG. 1, the present invention includes a pillowcase **10** that wraps around the foam body **80**. The foam body **80** is a viscoelastic polyurethane foam infused with a phase change material gel. The invention comes with an optional phase change material pack **20**. The phase change material pack **20** also comes with an optional phase change material pack casing **30**. The present invention includes an electrical plug **90** that can be used to charge the pillow's Cooler Modules. The Cooler Modules include a 1st Cooler Module **201**, 2nd Cooler Module **202**, 3rd Cooler Module **203**, 4th Cooler Module **204**, 5th Cooler Module **205**, 6th Cooler Module **206**, 7th Cooler Module **207**, 8th Cooler Module **208**, 9th Cooler Module **209**, 10th Cooler Module **210**, 11st Cooler Module **211**, 12nd Cooler Module **212**, 13rd Cooler Module **213**, 14th Cooler Module **214**, 15th Cooler Module **215**, 16th Cooler Module **216**, 17th Cooler Module **217**, 18th Cooler Module **218**, 19th Cooler Module **219**, 20th Cooler Module **220**, 21st Cooler Module **221**, 22nd Cooler Module **222**, 23rd Cooler Module **223**, 24th Cooler Module **224**, 25th Cooler Module **225**, 26th Cooler Module **226**, 27th Cooler Module **227**, 28th Cooler Module **228**, 29th Cooler Module **229**, 30th Cooler Module **230**, 31st Cooler Module **231**, 32nd Cooler Module **232**, 33rd Cooler Module **233**, 34th Cooler Module **234**, 35th Cooler Module **235**, 36th Cooler Module **236**, 37th Cooler Module **237**, 38th Cooler Module **238**, 39th Cooler Module **239**, and a 40th Cooler Module **240**. Having forty Cooler Modules allows selective cooling upon the pillow's active surface. The pillow's active surface is the surface in which certain Cooler Modules are active, corresponding to area that has pressure from supporting a user. The present invention includes a pillow antenna **41** with a wireless Bluetooth connector **40** that connects to any connected device **50** and its connected device antenna **51**. A user could monitor his sleep with his connected device **50**.

As seen in FIG. 2, the present invention includes a pillowcase **10** that wraps around the foam body **80**, which houses the Cooler Module columns. The Cooler Module columns have an optional phase change material pack **20** within an optional phase change material pack casing **30**. The Cooler Module columns include a 1st Cooler Module column **110**, 2nd Cooler Module column **120**, 3rd Cooler Module column **130**, 4th Cooler Module column **140**, 5th Cooler Module column **150**, 6th Cooler Module column **160**, 7th Cooler Module column **170**, 8th Cooler Module column **180**, 9th Cooler Module column **190**, and a 10th Cooler Module column **200**. Each Cooler Module column contains 5 Cooler Modules. The Cooler Module columns allow the Cooler Modules to be monitored and installed more efficiently. Be face change material pack **20** is installed directly above the Cooler Module columns to absorb the heat of the user over a higher surface area. The phase change material pack casing **30** allows for even distribution of phase change material within the phase change material pack **20**.

As seen in FIG. 3, the present invention has a top front side **300**, left front edge **301**, front right edge **302**, top right edge **303**, right rear edge **304**, bottom right edge **305**, bottom opening **306**, bottom rear edge **307**, bottom left edge **308**, front bottom edge **309**. The present invention's top front side **300** is directly above the present invention's front bottom edge **309**. The invention's left front edge **301** is directly

across from the invention's front right edge 302. The bottom opening 306 visually depicts where the Cooler Modules will be installed. The left front edge 301, front right edge 302, and right rear edge 304 are all the same height in order to create an evenly sized pillow for the user. The Peltier cooler board 310 allows the Cooler Modules installed onto it to be stable, therefore optimizing cooling. The present invention's Cooler Modules have a 1st Peltier Cooler 321, 2nd Peltier Cooler 322, 3rd Peltier Cooler 323, 4th Peltier Cooler 324, and a 5th Peltier Cooler 325. The Peltier Coolers use electric current to move heat from the pillow to the bottom side of the Peltier Cooler. The heat from the bottom of the Peltier Coolers is then transferred to the heatsinks groupings. The present invention has a 1st Heatsink Grouping 331, 2nd Heatsink Grouping 332, 3rd Heatsink Grouping 333, 4th Heatsink Grouping 334, and a 5th Heatsink Grouping 335. The heat sink groupings are fitted with liquid tubes 344 that absorb the heat from the heat sink groupings. The liquid tubes carry the heat from the heat sink to an outside radiator that is not shown. This radiator naturally releases heat from itself. The liquid moves throughout the liquid tubes 344 through a liquid pump that is not shown. The liquid cooling provides a quieter way to displace heat from the pillow. The pillow also has an air-cooling option that is faster, but louder than the liquid cooling option. The Cooler Modules use fans placed evenly throughout the Cooler Modules in order to evenly remove heat from the pillow. The hot air is moved out of the pillow through the air conduit 345. The present invention has a 1st fan 336, 2nd fan 337, 3rd fan 338, 4th fan 339, 5th fan 340, 6th fan 341, 7th fan 342, and an 8th fan 343. At the bottom of the Cooler Modules in both types of cooling are ceramic-plated fiberglass bottoms. The present invention has a 1st fiberglass bottom 326, 2nd fiberglass bottom 327, 3rd fiberglass bottom 328, 4th fiberglass bottom 329, 5th fiberglass bottom 330. These fiberglass bottoms provide heat insulation so that the bottom of the pillow does not get too hot. They also help to prevent heat from escaping into the rest of the pillow. The fiberglass bottoms have ceramic tops so that the heat sinks are secure within the Cooler Modules. The ceramic also provides insulation to the cooler module.

As seen in FIG. 4, a Cooler Module has a 1st LED Light Strip 410, and a 2nd LED Light Strip 420. The light strips are connected to a pressure sensor 450. The pressure sensor has a pressure sensor backing 460 for support. The LED light strips are connected to the pressure sensor 450. When the pressure sensor 450 senses a high enough pressure, the LED light strips will either turn off or change colors depending on the user's preference. The pressure sensors 450 also gauge the sleep patterns of the user based on movement. The connected device 50 can be used to change the pattern of the LED Light Strip and set different interactions with the 1st LED Light Strip 410 or the 2nd LED light Strip 420. Under the LED Light Strips and the pressure sensor is the Peltier Cooler. The Peltier Cooler has an upper ceramic substrate 430 and a lower ceramic substrate 440. The ceramic substrates are electrical insulators and keep the current within the Peltier Cooler for as much cooling efficiency as possible. In between the ceramic substrates are Thermoelectric Legs 470. Thermoelectric Legs 470 use electric current to move heat from one side to the other. Below the lower ceramic substrate lies the heatsink groupings 331. These heatsink groupings pull heat from the lower ceramic substrate which can be removed with the liquid tube 344 or the fans 336. Connected below the heatsink is the ceramic top of the fiberglass bottom 326. The fiberglass bottom 326 insulates the bottom of the pillow so that it does not heat up.

The present invention cooling pillow can have medical or nonmedical use with liquid or air cooling or a combination of liquid and air cooling.

- 5 The invention claimed is:
  1. A cooling pillow comprising:
    - a. a cooler module;
    - b. a heatsink module, wherein the heatsink module is a part of the cooler module;
    - c. a peltier cooler having a bottom side and a top side, wherein the peltier cooler transfers heat from the bottom side to the heatsink module, wherein the peltier cooler is a part of the cooler module;
    - d. a water tube, wherein the water tube absorbs heat from the heatsink module, wherein the water tube is fluidly connected to the heatsink module, wherein the water tube is a part of the cooler module;
    - e. a fiberglass bottom having a ceramic top, wherein the fiberglass bottom stabilizes the heatsink module, wherein the fiberglass bottom insulates the heat within the cooler module, wherein the fiberglass bottom is a part of the cooler module;
    - f. a pressure sensor, and wherein the pressure sensor measures pressure from a user, wherein the pressure sensor is a part of the cooler module;
    - g. a light strip, wherein the light strip is connected to the pressure sensor, and wherein the light strip lights up according to a connected device;
    - h. a fan, wherein the fan is formed in the cooler module, and wherein the fan blows air onto the heatsink module;
    - i. a pillow case, wherein the pillow case is situated around the pillow;
    - j. a pillow cover, wherein the pillow cover is situated around the pillow case, and wherein the pillow cover passively cools the user;
    - k. an air conduit, wherein the air conduit releases air from the fan, wherein the fan transfers heat from the heatsink out of the air conduit;
    - l. a foam body, wherein the foam body surrounds cooler module columns, and wherein the foam body is infused with phase change material gel;
    - m. an electrical plug, wherein the electrical plug powers the cooler module columns; and
    - n. a cooler module column, wherein the cooler module column comprises ten cooler modules, wherein the cooler module column arranged the cooler modules parallel to one another, and wherein the cooler module column receives electrical power from the electrical plug.
  2. The cooling pillow of claim 1, further comprising a phase change material pack, wherein the cooler module cools the phase change material pack.
  3. The cooling pillow of claim 1, further comprising a phase change material pack casing, wherein the phase change material pack casing encloses the phase change material pack.
  4. The cooling pillow of claim 1, further comprising a wireless connector, wherein the wireless connector includes a connection to a connected device, wherein the wireless connector is configured to receive control signals from the connected device.
  5. The cooling pillow of claim 1, further comprising:
    - a. a pillow antenna, wherein the pillow antenna is formed within the cooler module; and
    - b. a connected device, wherein the connected device is wirelessly connected to the pillow antenna.

6. The cooling pillow of claim 1, further comprising a radiator, wherein the radiator is a passive cooling radiator, and wherein the water tube transfers heat from the heatsink module to the radiator.

7. The cooling pillow of claim 6, further comprising a phase change material pack, wherein the cooler module cools the phase change material pack.

8. The cooling pillow of claim 6, further comprising a phase change material pack casing, wherein the phase change material pack casing encloses the phase change material pack.

9. The cooling pillow of claim 6, further comprising a wireless connector, wherein the wireless connector includes a connection to the connected device, wherein the wireless connector is configured to receive control signals from the connected device.

10. The cooling pillow of claim 6, further comprising:

a. a pillow antenna, wherein the pillow antenna is formed within the cooler module; and

b. a connected device, wherein the connected device is wirelessly connected to the pillow antenna.
